UNITED STATES PATENT OFFICE.

CHARLES BIANCHINI AND FRANÇOIS FERIER, OF LYON, FRANCE.

DESIGN FOR A TEXTILE FABRIC OR WALL-PAPER.

49,721.

Specification for Design.

Patented Oct. 3, 1916.

Application filed August 1, 1916. Serial No. 112,620. Term of patent 14 years.

To all whom it may concern:

Be it known that we, CHARLES BIANCHINI and FRANÇOIS FERIER, citizens of the French Republic, residing, respectively, at 4 Rue Vaucanson and 49 Rue Chaziere, Lyon, France, have invented a new, original, and ornamental Design for Textile Fabrics or Wall-Papers, of which the following is a specification, reference being had to the accompanying drawing, forming part thereof.

The drawing illustrates a repeating sur-

face pattern, the complete pattern and a portion of the repeat being shown.

We claim:

The ornamental design for a textile fabric or wall-paper, as shown.

CHARLES BIANCHINI.
FRANÇOIS FERIER.
